UNITED STATES PATENT OFFICE.

CARL W. WEISS, OF NEW YORK, N. Y.

EXPLOSIVE-ENGINE.

SPECIFICATION forming part of Letters Patent No. 592,034, dated October 19, 1897.

Application filed December 17, 1896. Serial No. 615,975. (No model.)

To all whom it may concern:

Be it known that I, CARL W. WEISS, a citizen of the United States, residing in the city and county of New York, in the State of New York, have invented certain new and useful Improvements in Explosive-Engines, of which the following is a specification, reference being had to the accompanying drawings, forming a part hereof.

10 This invention relates to explosive-engines of that class in which the basis of the explosive charge is supplied to the engine in the form of a liquid, which is then vaporized and mixed with the proper proportion of air.

15 The object of the invention is to produce an improved engine of this class in which the fouling and clogging of the various working parts, so common in engines of this class, shall be largely reduced and cleaning consequently required with less frequency, and which shall also be of exceedingly simple construction.

20 The invention will be explained hereinafter with reference to the embodiment thereof which I have chosen for illustration in the accompanying drawings, and in which—

25 Figure 1 is a vertical longitudinal section of an engine constructed and equipped in accordance with my invention. Fig. 2 is a detail view, in longitudinal section, of the oil-feed and a portion of the governor. Fig. 3 is an inside end view of the explosion-chamber and vaporizer.

30 The cylinder A of the engine may be of ordinary construction, except as hereinafter indicated, and may be provided with a water-jacket A', as usual. The casing A² of the cylinder is preferably extended forward to inclose the crank or crank-disks and to receive the bearings of the crank-shaft.

35 The trunk-piston B may be connected by a pitman B' to the crank-pin B², which may be carried by crank-arms or crank-disks B³, secured directly to the two parts of the crank-shaft C.

40 The chamber inclosed by the forward part of the casing A² constitutes a convenient air-compression chamber in which the air which is admitted through a suitable port shown in Fig. 1 at the lower side of the cylinder and covered by the piston in its forward movement, but opened as the piston reaches the

limit of its rearward movement, is compressed at each forward movement of the piston and which is connected through a suitable duct with the working cylinder A or the explosion-chamber, said duct having a port a, which is so arranged as to be closed against back pressure during the rearward movement of the piston. The cylinder A, having the inlet-port a, is also provided with an exhaust-port a', which is preferably covered by the piston except when the latter approaches the limit of its forward movement.

45 A deflector b may be formed upon or secured to the face of the piston B for the purpose of directing the incoming current of fresh air rearwardly into the explosion-chamber.

50 The parts thus far referred to are not directly concerned as to their particular construction and arrangement with the present invention and other arrangements may be substituted therefor.

55 The explosion-chamber in my improved engine is preferably formed by a shell D, which is secured directly to the end of the cylinder, with its larger open end toward the piston.

60 A supplementary shell D' may be secured to the cylinder outside of the shell D to protect the latter and to prevent excessive radiation, an aperture d being provided in the shell D' to permit the introduction of a heater for use in starting up the engine when it is cold.

65 For the purpose of increasing the vaporizing-surface within the explosion-chamber and of maintaining the temperature therein at such a degree that the engine will be self-igniting after it has been started, I prefer to support within the conical shell D a number of plates or ribs E E, which may be cast in one piece with a connecting-ring e. In order that the dead gases may be cleared out of the igniter and explosion-chamber thoroughly 70 after each explosion, the plates E E, as clearly shown, do not meet in the center, but are disposed about an open space, and a ring e is employed to secure them together in place of a plate, whereby as the current of air enters from the port a and is deflected by the deflector b into one side of the explosion-chamber, carrying with it the oil-spray from the extremity of the oil-duct, it drives out

before it from the other side of the explosion-chamber and igniter, between the plates E E, all of the dead gases that may be therein. It is obvious that these plates might be cast with 5 the shell D, but I prefer to form them separately in order to retard the conduction of heat from said plates to said shell. It will be understood, of course, that the said plates E E remain at a red heat during the operation 10 of the engine and that as the charge of the explosive mixture is compressed in the explosion-chamber by the return of the piston, the temperature is raised sufficiently to effect the ignition of the charge.

15 In accordance with my invention the oil to be vaporized is itself brought directly into the cylinder or into the explosion-chamber and is there converted into vapor and the vapor mixed with the proper volume of air. 20 To this end the oil is preferably fed through a nipple II, which projects through the jacked portion of the wall of the cylinder just in front of the shell D and in the path of the current of air as it enters from the compressor. The oil, which is fed by suitable means and stands in a small drop upon the end of the nipple, is caught by the blast of air and is blown in the form of spray into the explosion-chamber D and against the 25 heated surfaces and is immediately converted into vapor. The air which blows the oil from the nipple and converts it into spray at the same time supplies the volume of air necessary for the formation of the explosive mixture. The entire quantity of oil supplied at 30 the end of the nipple II is blown off, so that none remains to be carbonized on the nipple, and there is no opportunity for the spray or vapor to be condensed before the explosive 35 mixture is formed. Furthermore, there are no ducts or channels leading out of the cylinder to receive the vapor and to retard the ignition thereof, so that the combustion of the entire charge is complete and practically 40 instantaneous, giving the engine a very high efficiency.

In order that there may be no entrance of hot gases into the duct through which the oil is supplied, I prefer that the valve h, which 45 closes the duct against back pressure, shall be seated at the extremity of the nipple. This valve is an ordinary puppet-valve normally closed by a spring h'.

Any suitable means may be employed for 50 feeding to the nipple II the proper quantity of oil at each stroke of the engine, but I prefer to employ the means shown in the drawings in which a plunger G is operated from the crank-shaft. This plunger reciprocates 55 in a cylinder g, to which the oil is supplied through a lateral port g'. The plunger overruns the port only to a slight extent, just enough to force forward at each reciprocation a quantity of oil corresponding to that 60 which is to be introduced into the working cylinder, the rest of the oil in front of the plunger being returned through the port g'.

For the purpose of insuring at all times a close contact of the plunger with the wall of the cylinder g around the port g', the plunger 70 is slotted horizontally, as at g², so that the thinner portion of the plunger shall bear against the adjacent wall of the cylinder with a spring-pressure. The cylinder g is connected with the nozzle II by a suitable duct 75 h², and between the cylinder and the duct is a spring-actuated check-valve h³, which I have found to be effective in co-operation with the valve h in insuring regularity of feed and the delivery of a uniform quantity of oil at 80 each operation to the working cylinder.

The plunger G may be operated by any suitable means, but I prefer the arrangement shown in the drawings. As there represented, the plunger G has applied thereto a spring 85 g³, which acts to move the plunger backward after its forward movement, the spring being confined between a nut g⁴ on the plunger and the loose stuffing-box g⁵, and thereby acting as well to keep the packing around the plunger at 90 all times under the proper pressure without requiring screw adjustment of the gland. At its rear end the plunger bears against a rod f, which is mounted in a suitable guide on the frame of the engine and has pivoted upon its 95 end a tongue f², which has a very sharp edge f³, disposed in a horizontal plane. The tongue f² is held in normal position by a spring-plunger f⁴. The shaft C carries an eccentric C', (shown in dotted lines,) which operates a short lever c. To the upper end of the lever c is pivoted a screw-threaded shaft c', which carries a flat-faced nut c² to bear upon the block c³, having an incline c⁴. When the engine is running at a normal speed, the 100 end of the rod c', which is formed with a notch c⁵ to conform to the end of the tongue f², will strike the end of the rod f and operate the plunger to feed the proper quantity of oil for the next explosion, but when the engine is 105 running too fast the momentum of the rod and nut, as the latter travels up the incline c⁴, will throw the end of the rod c' above the end of the rod f, and the plunger will therefore be unaffected.

The shell D may be secured in place by any suitable means, but for convenience in construction and in permitting the shell to be removed readily, I prefer the means shown in Fig. 1, in which bolts d' pass through the 110 flange d² of the shell D' and engage the end of the cylinder-wall, while the shell D has a flange d³, which is clamped between the flange d² and the end of the cylinder or a ring thereon.

The mode of operation of my improved engine will be readily understood from the foregoing description without further explanation. It will be obvious also that as the entire oil-feeding duct is always filled with oil 120 to the valve-seat on the nipple within the working cylinder, and as the oil is constantly fed forward, there is no possibility of the hot gases working back into the oil-duct and con-

sequently there can be no fouling or clogging of the oil-feed. Furthermore, as the oil-duct is located in the wall of the cylinder, in the jacketed portion, it is kept cool always and the oil within it is not materially affected by the heat, while at the same time the explosion-chamber and vaporizer can remain unjacketed, thereby preventing absorption of heat and consequent reduction of temperature below that favorable for ignition.

In the practical operation of the engine it is found that there are no deposits of any appreciable amount upon any of the working parts of the engine except upon the walls of the working cylinder, where a thin deposit of carbonaceous matter is formed within the first few days of the operation of the engine, but does not materially increase thereafter, such deposit being moreover entirely harmless, and it is also found to be a fact, that the engine does not require to be cleaned for a long period of time of continuous operation, while in the same period of time engines of the same class heretofore devised require to be cleaned many times.

I claim as my invention—

1. In an explosive-engine, the combination with a water-jacketed working cylinder having an unjacketed explosion-chamber, of an oil-duct extended through the jacketed wall of the cylinder and terminating in the cylinder in front of the unjacketed explosion-chamber, a valve to close the extremity of said duct, and means to deliver the oil under pressure through said duct and to keep the duct constantly full.

2. In an explosive-engine, the combination with a cylinder and piston, an explosion-chamber in rear of the piston, a compression-chamber in front of the piston and an air-duct from said compression-chamber having a port opened by the piston at the forward limit of its stroke, of an oil-duct terminating in front of the explosion-chamber, and means to direct the current of air from said port when opened against the extremity of said duct to discharge the oil therefrom.

3. In an explosive-engine, the combination with a cylinder and piston, an explosion-chamber in rear of the piston, a compression-chamber in front of the piston and an air-duct from said compression-chamber having a port opened by the piston at the forward limit of

its stroke, of an oil-duct terminating in front of the explosion-chamber, a vaporizer located within the explosion-chamber, and means to direct a current of air from said port when opened against the extremity of said duct to discharge the oil therefrom.

4. In an explosive-engine, the combination with a water-jacketed working cylinder having an unjacketed explosion-chamber, of an oil-duct extended through the jacketed wall of the cylinder and terminating in the cylinder in front of the unjacketed explosion-chamber, a valve to close the extremity of said duct, a reciprocating plunger to force the oil through said duct, and a second valve interposed between said plunger and said duct, the said duct being continuous from the plunger to the valve at the extremity of the duct within the cylinder.

5. In an explosive-engine, the combination with the working cylinder, of a shell forming a vaporizing-chamber and having a flange to fit upon the end of the cylinder, a supplementary shell inclosing the first-named shell and having a flange to fit upon the flange of the first-named shell, and bolts passing through the flange of the supplementary shell and secured in the end of the wall of the cylinder, the flange of the first-named shell being clamped between the flange of the supplementary shell and the end of the cylinder.

6. In an explosive-engine, the combination with a cylinder having an explosion-chamber, of plates disposed radially in said explosion-chamber about an open central space and secured together by a ring.

7. In an explosion-chamber, the combination with a cylinder and piston, an explosion-chamber in rear of the piston, a compression-chamber, an air-duct from said compression-chamber having a port opened by the piston at the forward limit of its stroke, and means to direct the current of air from said port into the explosion-chamber, of plates disposed radially in said explosion-chamber about an open central space and secured together by a ring.

This specification signed and witnessed this 14th day of December, A. D. 1896.

CARL W. WEISS.
